[57] CLAIM

The ornamental design for a combined multiple cabinet and drawer storage unit, substantially as shown and described.

DESCRIPTION

FIG. 3
